APPARATUS FOR DRESSING GRINDSTONES

Howard C. Barbour, Elyria, and Franklin S. Miller, Amherst, Ohio, assignors to The Cleveland Quarries Company, Cleveland, Ohio, a corporation of Ohio

Application June 9, 1943, Serial No. 490,158

3 Claims. (Cl. 125—11)

This invention relates to apparatus for dressing the peripheries of grindstones such, for example, as the ordinary sandstone grindstones which have previously been cut and drilled centrally thereof.

The object of the present invention is to provide apparatus by which grindstones can be dressed rapidly and accurately without danger of chipping or breaking off portions of the stones at the edges of the annular surfaces being dressed. In other words, it is the principal object of the invention to provide a method and apparatus by which the output of the apparatus can be vastly increased over that of dressing methods and apparatus heretofore employed.

The invention may be further briefly summarized as consisting in certain details of construction and combinations and arrangements of parts which will be described in the specification and set forth in the appended claims.

In the accompanying sheets of drawings,

Fig. 1 is a partial side elevation and Fig. 2 is a partial plan view of one form of dressing machine, this machine being adapted for dressing grindstones of smaller sizes;

Fig. 3 is a partial side elevation and Fig. 4 is a partial plan view of a modified form of dressing machine, this machine being adapted for dressing somewhat larger grindstones;

Fig. 5 shows the rough grindstone and the two cutting disks at the start of the dressing operation, this view showing disks of the type illustrated in Figs. 1 and 2;

Fig. 6 is another view of the same near the completion of the dressing operation;

Fig. 7 is a view showing the completion of the dressing operation;

Fig. 8 is a view looking at the face of the grindstone and showing one of the cutting disks;

Fig. 9 is an enlarged sectional view through one of the cutting disks, this view being a sectional view along the line 9—9 of Fig. 2;

Fig. 10 is a view, similar to Fig. 5, of the cutting disks of Figs. 3 and 4, this view showing the start of the dressing operation;

Fig. 11 is a view of the same cutting disks, this view being similar to the view of Fig. 6 showing the dressing operation under way; and

Fig. 12 is a view of the cutting disks of Figs. 3 and 4, this view being similar to Fig. 7 and showing the dressing operation completed.

Referring now to the drawings, 15 represents a portion of the bed of a dressing machine similar to a lathe bed but omitting the supporting legs. Rotatably supported on the bed is a spindle

16 which is driven by a motor (not shown). This spindle is adapted to rotate the grindstone 17 to be dressed. The grindstone 17 is adapted to be secured against a shoulder 18 on the spindle by a clamping block or flange 19 and a nut 20. By simply removing the nut and slipping off the clamping block or flange 19, the grindstone can be slid off the spindle, and in similar fashion a new grindstone can be quickly applied to the spindle. The spindle is adapted to be adjustably supported on the bed by means of a pair of pillow blocks 21 and 22 movable along ways 23 of the bed.

On a pair of ways 24 and 25 of the bed are two slides 26 and 27 which are adapted to be simultaneously moved toward and away from each other by a handwheel 28 which is connected by means of a worm 29 shown by dotted lines in Fig. 2 to a righthand and lefthand threaded screw 30 which is supported at the front of the bed. The righthand and lefthand threaded portions of this screw are engaged by nuts carried by extensions 31 supported by the two slides 26 and 27, see particularly Fig. 1. The two slides 26 and 27 are provided with undercut ways 32 at right angles to the longitudinal axis of the machine on which are mounted two slides 33 which are movable back and forth with reference to the grindstone 17 by means of hand levers 33a. These slides carry two cutting disks 34 and 35 which are pitched downwardly and outwardly as shown in Figs. 1, 2, and 5 to 8 inclusive. The angle of the downward and outward pitch of the cutting disk is important both from the standpoint of effective cutting and from the standpoint of maintaining the disks in sharpened condition. We find that an angle of not more than 17° and not less than 14° is satisfactory for this purpose; that is to say, the disks should be pitched downwardly and outwardly to this extent. In other words, the cutting disks are so supported that they are pitched outwardly this definite amount and are pitched downwardly the same amount. By reference to Fig. 9 it will be seen that the disks 34 and 35 have beveled edges 36 which are beveled to substantially the same extent that the disks are pitched downwardly and outwardly.

With the apparatus described above, the grindstone is dressed in the following manner:

Assuming that the grindstone 17 with its rough outer periphery which is to be dressed is attached to the spindle 16, the spindle is rotated and the handwheel 28 is turned to move the screw 30 and bring the disks simultaneously to-

ward each other until their cutting edges engage the grindstone, whereupon the disks will be rotated by contact with the rotating grindstone. The operator continues to turn the handwheel 28 bringing the two disks toward each other until a ridge 17a (see Fig. 6) is left at the center of the periphery of the grindstone. Then one of the disks, in this instance the disk 34, is moved laterally from the periphery of the grindstone by the operator turning one of the hand levers 33a until the disk is substantially in the position shown in Fig. 7, whereupon movement of the screw 30 is continued, causing the other cutter, in this instance the disk 35, to be moved in the same direction as before to cut through the ridge 17a on the grindstone.

In Fig. 7 is shown the grindstone 17 with its periphery completely dressed, whereas in Fig. 5 is shown the grindstone 17 at the start of the dressing operation. Fig. 6 shows the grindstone partly dressed ready to have the cutter 34 backed away from it and to allow the other cutter to remove the ridge 17a. In this manner chipping of the edge of the grindstone is avoided as would be likely to occur if a single cutting disk were employed and the disk were moved across the entire periphery of the grindstone.

Referring now to Figs. 3 and 4 and Figs. 10, 11 and 12, it will be seen that in this instance the dressing machine has a bed 37 which is provided with a rotatable spindle 38 which is adapted to receive a grindstone 39 whose periphery is to be dressed, the spindle being motor driven as in the previously described construction. The bed 37 has ways 40 on which is movable a slide 41 having undercut ways 42 (see Fig. 3) at right angles to the longitudinal axis of the machine and on these last mentioned ways is adapted to be moved a second slide 43 which can be moved toward and from the axis of the machine by rotating a lever 44 to adapt the machine for grindstones of different diameters. The slide 41 has an adjustable stop 45 which limits the movement of the slide 43 toward the axis of the machine.

The slide 43 has a slide 46 which carries two supports 47 and 48 for the cutting disks 49 and 50. The supports 47 and 48 can be moved along ways 51 to adjust the distance between the disks 49 and 50 and then are adapted to be clamped in position. The slide 46 carries a screw 52 which can be turned by a handwheel 53 to adjust the position of the disks 49 and 50. This screw 52 has a continuous one-way thread which engages a nut carried by the slide 46.

The cutting disks 49 and 50 are arranged like the cutting disks 34 and 35 of the construction first described, that is to say, they have a downward pitch relative to the machine and an outward pitch relative to each other of the same angular amounts as in the first construction. Likewise, the cutting disks are provided with beveled edges 54 similar to the beveled edge 36 of each of the cutting disks of the first described construction. The edge 54 of each of the disks 49 and 50 is beveled at an angle substantially equal to the angle of the downward and lateral pitch of the cutting disks.

With this construction both disks move simultaneously in the same direction. The screw is rotated in a direction to cause one of the disks to start the dressing operation, in this instance the disk 49, as shown in Fig. 11, and after this disk has traveled a portion of the distance across the periphery of the grindstone, the direction of rotation of the screw 52 is reversed by turning

the handwheel in the opposite direction, bringing the disk 50 into operation so as to complete the dressing operation. If desired, the disk 50 may be moved entirely across the periphery of the grindstone so as to insure a completely smooth periphery, this being shown in Fig. 12. In this manner the likelihood of chipping the edge of the grindstone is eliminated, as in the case of the construction shown in Figs. 1 and 2.

Fig. 10 shows the arrangement with a disk 49 about to start the dressing operation. Fig. 11 shows the dressing operation partially completed, and Fig. 12 shows it entirely completed.

When the dressing operation is completed and another grindstone is to be placed on the spindle 38, one of the cutting disks, in this instance the disk 49, is backed away with respect to the disk 50 so as to allow the grindstone to be placed in position without injuring either disk, and this is accomplished by mounting the disk 49 (see Figs. 3 and 4) on a slide 55 which is movable along undercut ways of the support 47 by rotating a hand lever 56. Then as soon as the grindstone is in position on the spindle the cutting disk 49 and the slide 55 are moved forward so as to position the disk 49 in line with the disk 50. Or, if desired, both disks can be simultaneously backed away and moved forward by turning the hand lever 44.

It will be understood that the spindle 38 and the grindstone 39 are driven by a motor not shown, and the grindstone is attached to the spindle as in the first described construction, and that at the beginning of the dressing operation the first disk 49 (or the disk 50) is rotated by its contact with the grindstone, and after the dressing operation is substantially completed and the direction of the screw 52 is reversed, the cutting disk 50 (or the disk 49) is immediately rotated by contact with the grindstone. Likewise, it will be understood that the cutting disks 49 and 50 are self-sharpening, as in the construction first described.

Thus it will be seen that the objects of the invention are attained very effectively by either construction, that is to say, the cutting disks have long life and are self-sharpening, and the machine has a very high output so that the cost of dressing each grindstone is reduced to a minimum and at the same time the likelihood of chipping or breakage of the edge of the grindstone is substantially eliminated.

While we have illustrated two embodiments of the invention, we do not desire to be confined to the precise details of construction of the apparatus illustrated and described, but aim in our claims to cover all modifications which do not involve a departure from the spirit and the scope of the invention.

Having thus described our invention, we claim:

1. In a machine for dressing grindstones, a frame having a rotatable spindle on which a grindstone is adapted to be mounted, and means for dressing the periphery of the grindstone comprising a pair of slides on the frame of the machine carrying a pair of cutting disks, each cutting disk being pitched downwardly and outwardly and having a self-sharpening beveled cutting edge, and means for simultaneously feeding the disks toward each other for dressing the major portion of the periphery of the grindstone, and means for backing away from the periphery of the grindstone one of the disks so that by continued feeding of the other disk in the same di-

rection as before the remainder of the periphery of the grindstone can be dressed.

2. In a machine for dressing grindstones, a frame having a rotatable spindle on which a grindstone is adapted to be mounted, and means for dressing the periphery of the grindstone comprising a slide on the frame, a pair of supports on the slide carrying a pair of cutting disks, each cutting disk being pitched downwardly and outwardly with respect to the horizontal axis of the 10 grindstone, and means for bringing one and then the other of the disks into contact with the periphery of the grindstone, each disk having a self-sharpening beveled cutting edge.

3. In a machine for dressing grindstones, a 15

frame having a rotatable spindle on which a grindstone is adapted to be mounted, and means for dressing the periphery of the grindstone comprising a pair of cutting disks slidably supported on the frame, each cutting disk being pitched downwardly and outwardly with respect to the horizontal radius of the grindstone and having a self-sharpening beveled cutting edge, and means for manipulating the disks in the dressing operation so that a portion of the periphery of the grindstone will be dressed by one disk and the remaining portion by the other disk.
